UNITED STATES PATENT OFFICE.

ALBERT G. GOWAN, OF CORSICANA, TEXAS.

BALING-PRESS.

SPECIFICATION forming part of Letters Patent No. 615,159, dated November 29, 1898.

Application filed June 30, 1897. Serial No. 642,937. (No model.)

To all whom it may concern:

Be it known that I, ALBERT G. GOWAN, a citizen of the United States, residing at Corsicana, in the county of Navarro and State 5 of Texas, have invented a new and useful Baling-Press, of which the following is a specification.

My invention relates to baling-presses, and particularly to that class wherein the plunger-beam is actuated by cam-pressure, the cam receiving its motion from a sweep operated by horse-power or its equivalent; and the object in view is to provide coöperating main and auxiliary cam-faces adapted for 15 successive application of pressure to the plunger-beam, whereby the maximum speed of movement is communicated to the plunger-beam during the first operation of the stroke and whereby the speed is decreased 20 and the power proportionately increased as the plunger approaches the limit of its movement.

Further objects and advantages of this invention will appear in the following description, and the novel features thereof will be 25 particularly pointed out in the appended claims.

In the drawings, Figure 1 is a perspective view of a baling-press constructed in accordance with my invention. Fig. 2 is a plan view of the operating mechanism, showing in full lines the positions which the parts occupy during the first or preparatory portion 30 of a stroke and in dotted lines the positions 35 which the parts occupy during the succeeding portion of the stroke when the speed of movement is secondary to the power.

Similar numerals of reference indicate corresponding parts in both figures of the drawings.

1 designates a base, upon one end of which is arranged a baling-chamber 2, and 3 represents a plunger operating in the baling-chamber and having a plunger-beam 4. The plunger-beam operates between upper and lower 45 parallel guide-plates 5 and 6 and also between axially-vertical guide-rolls 7, and to the beam is attached a rebounding spring 8, which, however, may be omitted when it is desired to depend upon the elasticity of the material baled 50

to return the plunger to its initial position. The sweep 9 is attached to a cam-head 10, fulcrumed at 11 upon the base and adapted to bear at its face against a terminal contact-point consisting in the construction illustrated of an antifriction-roll 12, mounted on the end of the plunger-beam. In connection with this main cam, however, I also preferably employ an auxiliary cam 13, which is arranged on the sweep 9 in advance of the 55 initial portion of the curve of the main cam and is at a still more abrupt curve than the same to coöperate with a bearing-point consisting of an antifriction-roller 14, located on the plunger-beam in advance of the bearing-point 12 and in a different horizontal plane therefrom. The object in arranging the bearing-point 14 and the auxiliary cam 13 in a different plane from the bearing-point 12 and the cam 10 is to enable the auxiliary cam to 60 actuate the plunger-beam initially and then transfer the operation to the main cam by bringing the face of the main cam into contact with the main bearing-point 12 before the auxiliary cam releases the auxiliary bearing-point 14. This produces a continuous 65 operation and avoids jar and at the same time gives a rapid initial motion to the plunger during that portion of the stroke when the material being baled is loose. The rapidity 70 of motion imparted by the main-cam face to the plunger-beam gradually decreases from the initial point toward the terminal point.

Various changes in the form, proportion, and the minor details of construction may be 75 resorted to without departing from the spirit or sacrificing any of the advantages of this invention.

Having described my invention, what I claim is—

1. In a baling-press, a plunger-operating mechanism including a rebounding plunger-beam, a main cam having a face for coöperation with a main bearing-point on the plunger-beam, and an auxiliary cam arranged in 80 advance of the initial point of the main cam for coöperation with an auxiliary bearing-point on the plunger-beam in a different plane from the main bearing-point, the face of the auxiliary cam receding from the fulcrum- 85

point of the main cam in a more abrupt curve than the initial portion of the face of the main cam, substantially as specified.

2. In a baling-press, a plunger-operating mechanism including a rebounding plunger-beam provided with main and auxiliary bearing-points arranged in different planes, and connected coöperating main and auxiliary cams adapted for successive contact respectively with said main and auxiliary bearing-

points, the auxiliary cam being arranged in advance of the initial point of the main cam, substantially as specified.

In testimony that I claim the foregoing as my own I have hereto affixed my signature in the presence of two witnesses.

ALBERT G. GOWAN.
